UNITED STATES PATENT OFFICE.

WALLACE C. SABINE, OF BOSTON, MASSACHUSETTS, ASSIGNOR TO H. W. JOHNS-
MANVILLE COMPANY, A CORPORATION OF NEW YORK.

SOUND-ABSORBING WALL OR CEILING.

1,205,939.

Specification of Letters Patent. Patented Nov. 21, 1916.

Application filed November 29, 1915. Serial No. 64,150.

To all whom it may concern:

Be it known that I, WALLACE C. SABINE, a citizen of the United States of America, residing at Boston, county of Suffolk, State 5 of Massachusetts, have invented certain new and useful Improvements in Sound-Absorbing Walls or Ceilings, of which the following is a specification.

My invention relates generally to the 10 prevention or correction of a certain class of acoustical difficulties arising in auditoriums, lecture rooms, offices and the like and due to excessive reverberation, echo, and injurious focusing of sound and similar 15 causes.

More specifically my invention is designed 20 to produce a type of wall or ceiling surfacing or covering which shall be efficient in the absorption and transmission of sound 25 and also hygienic in character.

In some aspects the present invention is 30 an improvement on that disclosed in U. S. Patent No. 1,119,543 granted December 1, 1914, to Rafael Guastavino and myself as 35 joint inventors of an improved wall or ceiling for auditoriums and the like, having in combination a supporting masonry structure and attached thereto an exposed inner 40 layer of finished masonry, sponge-like in structure, the latter having pores which have grid walls and are inter-communicating throughout the mass and openly penetrate the exposed finished surface, the said pores being of such proportional and variant dimensions 45 that said inner masonry material possesses the property of absorbing in excess of ten per centum of sounds lying in pitch between middle C and a third octave above middle C. This masonry material is designed 50 to take the place of felt which is in large use today in acoustical correction in consequence of my investigations. Such masonry material has the advantage of being durable, vermin free, and fireproof. It 55 is, however, because of its porosity, not entirely hygienic and therefore not acceptable as an exposed surface under many conditions.

It is the object of this invention to provide 55 walls and ceilings which, while retaining the many advantages of sound absorbing masonry, are hygienic and non-porous in their outer exposed surface. This result is accomplished by combining an outer 55 impervious, non-porous but flexible membrane with an under structure of porous

masonry material. The nature of the masonry material is immaterial to this invention provided only that it be sound absorbent. It may be ceramic or non-ceramic. 60 This impervious exposed membrane may be made of muslin or other fabric stretched between battens and then sized. It thus loses its porosity but remains flexible. Or the muslin may be rendered impervious by the 65 application thereto of a covering layer of paper. Membranes prepared in different ways have different weights and different tensions, these properties having perceptible effects on the acoustical value of the result- 70 ing combination, as will be explained later. The sizing of the stretched muslin or pasting of paper thereon tends to shrink the fabric and increase the tension of the sheet.

A porous covering transmits the sound 75 from the room to the sound absorbing masonry material beneath, partially by direct air communication through the open pores, and partially by itself yielding in vibration, and in this process of transmission it itself 80 acts as a sound absorbent. The impervious non-porous membrane herein described transmits the sound to the sound absorbing masonry beneath only by yielding in vibration. The present invention, therefore, in 85 an endeavor to secure a smooth hygienic surface, loses somewhat in acoustical efficiency under certain conditions. Properly executed, however, with a sufficiently light membrane the loss of acoustical efficiency 90 is not great and under certain conditions, particularly in school rooms and the like, hygienic considerations more than compensate for this slight loss. While there is this loss in aggregate sound absorbing power 95 considering sounds of all audible pitch, so far as sounds of the ordinary range of pitch of the speaking voice are concerned, the capacity of resonance to such sounds in the stretched membrane can be made to heighten 100 the sound absorbing action of the complete structure. By resonance, in the sense here used, is meant the capacity for sympathetic vibration. These sympathetic and impressed vibrations act to partly absorb and partly 105 transmit the sound waves to the sound absorbing masonry material beneath. The absorbing power of the combination, membrane and masonry beneath, is thus concentrated over certain ranges of pitch. If the 110 weight and tension of the membrane are so adjusted that this concentration of absorb-

ing power is in the middle register and the immediately upper register, the vital range of pitch, the result is positively advantageous for all practical purposes in reducing 5 the echo and reverberations of ordinary speech, even though the echo and reverberation effects may not be as greatly reduced for very high pitched notes.

Accordingly the invention primarily consists in a porous artificial masonry material capable of absorbing sound to a high degree and of an impervious membrane stretched freely in front of it and capable of transmitting by its yielding in vibration a considerable portion of the sound to the masonry beneath.

The best form of construction at present known to me embodying my invention is shown in the accompanying drawings in 20 which--

Figure 1 is a cross section of a wall treated in accordance with one manner of applying my invention, and Fig. 2 is a similar view showing a wall treated in accordance with 25 another manner of applying my invention.

Throughout the drawings like reference characters indicate like parts.

1, is the main wall structure or backing, which may be of any ordinary building 30 material giving the desired strength and general structural qualities.

2, 2, are sections or panels of porous, sound absorbing masonry material such as is disclosed in Patent No. 1,119,543 before referred to, which are set in cement 3. Over the surface so formed is stretched the non-porous sound absorbing membrane 4, such as sized muslin which may be fastened to battens 5, 5, or otherwise secured to the exterior of the masonry and which forms the interior surface of the room exposed to view by the occupants. The membrane 4, is stretched by the act of attachment or by subsequent treatment with size sufficiently to 45 secure the desired degree of resonance to transmit sounds in the middle register, and is preferably parallel to the main wall surface leaving a narrow air space between the masonry material and the back of the membrane.

In Fig. 2 the panels 2, 2, of porous masonry material are fastened to the wall 1, in any convenient manner, as by application of a plaster-like layer thereof, and the 55 membrane impervious and non-absorbent of moisture, dust and germs fastened to battens 5, 5, is composed of a sheet of muslin 6, or other light textile fabric to the face of which is pasted or otherwise attached 60 sheets of paper 7.

In operation the sound waves in or near

the middle register striking the stretched membrane 4, or 7, are largely transmitted therethrough by its yielding in vibration, and are absorbed by the porous masonry material 65 beneath.

The porous masonry shown in Fig. 2 may be composed of a mixture of coarse sand, or broken stone, having all particles of substantially the same size, and mixed with a small 70 portion of Portland cement, say one third part by weight, and applied with a trowel. The small quantity of cement causes the particles of mineral aggregate to adhere one to another at their points of contact leaving 75 spaces between.

The advantages of a wall or ceiling constructed in accordance with this invention are that it will be sufficiently absorbent to sound to have high corrective acoustical 80 value in auditoriums and the like, and at the same time have the hygienic and decorative quality of an impervious surface in the outer membrane and the durable, vermin-proof and incombustible character of masonry in 85 the inner layer.

Various changes could be made in the details of the preferred construction herein shown and described without departing from the substance of the invention so long as the 90 principle of arrangement and operation of parts above set out, is retained.

Having described my invention, I claim:

1. A sound absorbing, hygienic and decorative surfacing for walls and ceilings, comprising in combination a porous, sound absorbing layer of masonry material and a relatively impervious non-porous elastic membrane composed of sheets of textile material treated with size affixed thereto stretched under tension in front of the first mentioned layer and separated therefrom by an intervening air space.

2. A sound absorbing, hygienic and decorative surfacing for walls and ceilings, comprising in combination a porous, sound absorbing layer of masonry material, a relatively impervious, non-porous elastic membrane stretched in front of the first mentioned layer under a tension sufficient to render it resonant to sounds in the middle and immediately upper registers and separated therefrom by an intervening air space and a series of widely spaced supports projecting slightly beyond the outer surface of the 115 porous masonry, to which supports the stretched membrane is attached.

WALLACE C. SABINE.
